UNITED STATES PATENT OFFICE.

NELSON M. WATSON, OF DETROIT, MICHIGAN.

COIN-ACTUATED MEDICAL BATTERY.

SPECIFICATION forming part of Letters Patent No. 684,014, dated October 8, 1901.

Application filed January 28, 1901. Serial No. 45,024. (No model.)

To all whom it may concern:

Be it known that I, NELSON M. WATSON, a citizen of the United States, residing at Detroit, in the county of Wayne, State of Michigan, have invented certain new and useful Improvements in Coin-Actuated Medical Batteries; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to coin-actuated medical batteries; and it consists in the construction and arrangement of parts herein-after fully set forth, and pointed out particularly in the claims.

The object of the invention is to provide simple and efficient means whereby upon the insertion of a coin and the operation of a movable handle of the device an electric current may be closed through the hands of the operator, the arrangement being such as to enable the volume of current to be regulated and a further arrangement provided for cushioning the return of the movable handle when released. The above object is attained by the mechanism illustrated in the accompanying drawings, in which—

Figure 1 is a front elevation of the machine. Fig. 2 is a rear elevation of the operative mechanism, the electric circuit showing in diagram and the base of the machine appearing in transverse section. Fig. 3 is a horizontal section as on line 3 3 of Fig. 2. Fig. 4 is an enlarged detail in section of a portion of the operative mechanism. Fig. 5 is also an enlarged detail in section herein-after explained.

Referring to the characters of reference, 1 designates a suitable base, upon which the mechanism is mounted, said mechanism being inclosed in a suitable case 2, having a glass front, whereby the operative parts and indicating-scale are rendered visible. Fixed to one side of the base is a handle 3, adapted to be grasped by the hand of the operator. At the opposite side of the machine is a rotary handle or crank 4, attached to the shaft 5, suitably journaled in the machine. Con-

nected with the fixed handle 3 is one side of an electric conductor or circuit 6, which leads to a battery or source of electricity 7 and includes the coil of the electromagnet 8. The opposite side of said line leads from the battery and terminates in a spring-terminal or contact-point 10, insulated from the metal base 11 of the machine by the non-conducting contact-block 12, upon which the spring-terminal is mounted. Pivoted upon the metallic base 11 is a bell-crank lever 13, one arm of which stands normally adjacent to the spring-terminal 10 and is adapted to be moved into contact therewith, said arm carrying a beveled face 14, (see Fig. 3,) describing the segment of a circle and adapted to embrace and temporarily confine the edge of a coin. A vertical coin-chute 15 is pivoted upon a shaft 16 and is adapted to receive and direct the coin into contact with the beveled face 14 of the bell-crank lever 13. Upon the shaft 5, carrying the crank or handle 4, is an eccentric 17, (see Fig. 4,) adapted to engage the inner end of a horizontally-movable pin 18, whose opposite end passes through the side of the metal base 11 and bears against the coin-chute 15. As the coin is directed into the chute 15, it passes downward and lodges against the beveled face 14 of the bell-crank lever 13, and at the same time the upper arc of the coin is engaged by the confining-channels of said chute. A rotation of the crank or handle 4 will then carry the eccentric 17 against the pin 18 and cause said pin to tilt the coin-chute 15 upon its shaft or pivot 16, thereby crowding the edge of the coin against the beveled face 14 of the bell-crank lever and forcing the end of said lever into contact with the spring-terminal 10, thereby closing the circuit through said terminal and through the metal base and shaft 5 to the handle or crank 4, placing said handle, together with the handle 3, in circuit with the battery and completing the circuit through the body of the operator when said handles are held by the operator's hands. As the coin-chute 15 is tilted farther through the operation of the handle 4 the coin is carried past the inclined face 14 of the bell-crank lever, when it is released and discharged into the base of the machine. Mounted upon the shaft 5 and attached at one end thereto is a

- coiled spring 19, whose opposite end is attached to the base and whose tension is exerted to return the shaft 5 and handle 4 to their normal position after an operation.
- 5 When the handle 14 is released by the operator, said spring returns it, and at the same time the arm 20, mounted upon the shaft 5 and adapted to move in frictional contact therewith, engages the end 21 of the bell-
- 10 crank lever extending into the path of said arm and actuates said lever to carry the opposite end thereof from contact with the spring-terminal 10 and break the electric circuit, the chute 15 being restored to its normal position by the spring 22, adjacent thereto.
- To provide an intermittent current when the handles are placed in circuit with the battery, a conductor 23 (see Fig. 2) is employed, which is connected with the coil of
- 20 the electromagnet and leads to a binding-screw 24, connected with a contact-arm 25, (see Fig. 1,) carrying an adjustable contact-screw 26, whose point stands adjacent to a vibrator 27 in circuit with the metal base 11
- 25 and in the field of said electromagnet, so that upon the closing of the main circuit or contact-terminal 10 the circuit is also closed through said vibrator, thereby putting said vibrator in operation.
- 30 To provide for regulating the current which flows through the handles of the machine and to the operator grasping said handles, the core (not shown) of the electromagnet is covered by a movable sleeve 27, which embraces said
- 35 core and which is connected, by means of a pin 28, with a bracket 29, mounted upon the vertically-movable rod 30, which is provided at its lower end with a rack which meshes with a pinion 32 on the shaft 5, whereby when said
- 40 shaft is rotated through the handle 4 the rod 30 is raised, carrying upward the sleeve 27, embracing the core of the magnet, and effecting a proportional increase in the flow of current. In order to register the amount of cur-
- 45 rent being used, there is mounted in the bracket 29 and movable therewith a rack-bar 33, (see Fig. 2,) whose upper end engages a pinion 34, mounted on the shaft of a hand 35, adapted to sweep the graduated face of a
- 50 dial 36, whereby as said rack-bar is carried upward with the operation of withdrawing the sleeve from the core of the magnet it causes the indicating-hand 35 to register the amount of current on said graduated scale.
- 55 When the crank or handle 4 has been caused to make nearly a complete revolution, considerable tension is placed upon the spring 19, which upon the release of the handle will return said handle with a force liable to cause
- 60 injury to the parts. To obviate a forced return of the handle 4 upon its release, the lower end of the rod 30 is provided with a piston 37, (shown by dotted lines in Fig. 2,) which is adapted to reciprocate in a closed air-cylinder
- 65 38 and which is drawn upward as said rod is raised to actuate the sleeve of the core and the hand of the dial, so that said piston upon

the release of the handle 4 after an operation of the machine is at the top of the cylinder, whereby an air-cushion is formed in said cylinder below the piston, which prevents a sudden return of the handle 4, but allows said parts to gradually resume their former or normal position.

In the face of the case 2 is a coin-opening 75 39, which directs the coin to the chute 15.

In the operation of this device a coin is placed in said opening 39 and is conveyed by the chute 15 to the curved beveled face 14 of the bell-crank lever 13, when the operator 80 grasps the handles and moves the handle 4 so as to cause the pivoted chute 15 to force the coin against the beveled face of the bell-crank lever and carry the point of said lever into contact with the terminal 10, thereby 85 placing the handles in circuit with the battery and the vibrator through the electromagnet. The initial current is comparatively weak, owing to the fact that the sleeve 27 covers the core of the magnet. After the handles have 90 been placed in circuit, however, any desired increase in the flow of current may be effected by rotating the handle 4 so as to withdraw the sleeve from the core of the magnet, as before described. When the coin is forced 95 past the beveled face of the bell-crank lever, it passes from the chute 15, so that when the handle 4 has been released and the parts restored to the normal position the machine cannot be again operated until another coin 100 is inserted.

Having thus fully set forth my invention, what I claim as new, and desire to secure by Letters Patent, is—

1. In a machine for the purpose set forth, 105 the combination of an electric circuit having one terminal in a fixed handle and the other in a spring-contact, a bell-crank lever adjacent to said contact, said lever carrying a beveled face adapted to engage the margin 110 of a coin, a movable coin-chute, adapted to direct a coin to the beveled face of said lever, a rotary shaft adapted to move said coin-chute to cause the coin therein to move said lever into contact with said terminal and an 115 operative handle upon said shaft.

2. In a machine for the purpose set forth, the combination of a normally open electric circuit, a fixed handle in which one end of 120 said circuit terminates, a spring-contact in which the other end of said circuit terminates, a movable conductor agent adapted to move into and out of engagement with said spring-contact to place said movable agent in circuit with the source of electricity, said 125 movable agent carrying a contact-face adapted to be engaged by a coin, a movable coin-chute adapted to direct a coin to the contact-face of said agent, a movable handle, means connecting said movable handle with said 130 coin-chute, whereby, by a movement of said handle the coin-chute may be actuated to cause the coin therein to engage and carry the movable agent into contact with said

spring-terminal and establish a continuity of the circuit through said movable parts to said movable handle.

3. In a machine for the purpose set forth, the combination of an electric circuit including a source of electricity, and an electro-magnet, a fixed handle connected with one terminal of said circuit, a contact-spring connected to the opposite terminal of said circuit, a movable handle, a rotary shaft carrying said handle, a movable coin-chute connected with said movable handle and adapted

by its movement to cause a coin to actuate said movable agent and carry it into contact with said spring-terminal, a pinion on said shaft, a rack engaging said pinion, a spring for returning said shaft, an air-cylinder and a piston on said rack working in said cylinder.

In testimony whereof I sign this specification in the presence of two witnesses.
